(57) **CLAIM**

I claim the ornamental design for a underwater LED light, as shown.

DESCRIPTION

FIG. 1 is a perspective view of the underwater light emitting diode light;

FIG. 2 is a top plan view of the underwater light emitting diode light according to FIG. 1;

FIG. 3 is a front elevational view of the underwater light emitting diode light according to FIG. 1;

FIG. 4 is a bottom plan of the underwater light emitting diode light according to FIG. 1; and,

FIG. 5 is a side elevational view of the underwater light emitting diode light according to FIG. 1.

1 Claim, 3 Drawing Sheets

FIG.1.

FIG.2.

FIG. 3.

FIG. 4.

FIG. 5.
